US0D1108874S

(12) **United States Design Patent** (10) **Patent No.:** **US D1,108,874 S**
(45) **Date of Patent:** **** Jan. 13, 2026**

(54) **BAKEWARE**

(71) Applicant: **Shenzhen Xiaomo Technology Co., Ltd.**, Shenzhen (CN)

(72) Inventor: **Lunqiang Li**, Shenzhen (CN)

(73) Assignee: **Shenzhen Xiaomo Technology Co., Ltd.**, Shenzhen (CN)

(**) Term: **15 Years**

(21) Appl. No.: **29/958,487**

(22) Filed: **Aug. 20, 2024**

(51) LOC (15) Cl. **07-02**

(52) U.S. Cl.

USPC **D7/357; D7/354**

(58) **Field of Classification Search**

(57) **CLAIM**

The ornamental design for a bakeware as shown and described.

DESCRIPTION

FIG. 1 is a front, right and top perspective view of a bakeware, showing my new design.

FIG. 2 is a rear, left and bottom perspective view thereof.

FIG. 3 is a front elevation view thereof.

FIG. 4 is a rear elevation view thereof.

FIG. 5 is an enlarged left side elevation view thereof.

FIG. 6 is an enlarged right side elevation view thereof.

FIG. 7 is a top plan view thereof.

FIG. 8 is a bottom plan view thereof; and,

FIG. 9 is a front, left and top perspective view of the bakeware of FIG. 1 shown with an unclaimed cover.

The dashed broken lines shown in FIGS. 1 to 8 depict portions of the bakeware that form no part of the claimed design. The broken lines shown in FIG. 9 depict environmental structure and form no part of the claimed design.

1 Claim, 9 Drawing Sheets
